UNITED STATES PATENT OFFICE

2,579,396

METHOD OF MAKING REFRIGERATOR CABINETS

Lawrence A. Philipp, Detroit, Mich., assignor to
Nash-Kelvinator Corporation, Detroit, Mich., a
corporation of Maryland

Original application April 3, 1946, Serial No.
659,254. Divided and this application July 31,
1947, Serial No. 765,173

3 Claims. (Cl. 29—148.2)

1

This invention relates to refrigerators, and, more particularly, to an improved domestic refrigerator that can be fabricated economically to provide greater refrigerated volume at lower cost than has heretofore been possible.

The present application is a division of my copending application, Serial No. 659,254, filed April 3, 1946 for Refrigerating Apparatus, now Patent No. 2,484,310 issued October 11, 1949.

It has been common practice in the refrigeration art to provide inner and outer shells formed of sheet metal suitably secured together. The inner shell is smaller than the outer shell to provide a space for insulating material between the inner and outer shells. This type of construction has been relatively expensive because of the necessity of fabricating the inner and outer shells of sheet material and securing them together with the insulation in place. It has, therefore, been impossible to provide a relatively large sized domestic refrigerator that could be sold at prices within the economic range of many thousands of purchasers.

I have found that refrigerators can be produced more economically by forming an outer shell or cabinet of sheet metal having inwardly directed vertically extending grooves to receive an inner liner in the form of a plastic shell adapted to be inserted and locked in place after insulation is positioned in the outer shell.

An object of this invention resides in the development of an improved method of fabricating domestic refrigerators wherein an outer metallic shell is provided with spaced grooves to receive an inner shell formed of plastic material spaced from the outer shell to form an insulation space therebetween.

A further object of the invention resides in the provision of a domestic refrigerator that can be fabricated economically of an outer metallic shell having spaced channels to receive a plastic liner to define a food storage compartment.

Yet a further object of the invention is to provide a domestic refrigerator capable of economical fabrication to provide an outer shell capable of functioning as a refrigerant heat dissipating condenser element, and an inner shell formed of non-conducting material to improve the heat insulating characteristic of the refrigerator.

Another object of the invention resides in the development of an improved method of positioning a liner in a metallic refrigerator cabinet and securing the liner in place to provide a space for insulation between the liner and cabinet and to define a food storage compartment.

2

Other objects and advantages of this invention will be apparent from the following detailed description considered in connection with the accompanying drawings, submitted for purposes of illustration only and not intended to define the scope of the invention, reference being had for that purpose to the subjoined claims.

In the drawings, wherein similar reference characters refer to similar parts throughout the several views:

Fig. 1 is a front elevation of a domestic refrigerator embodying this invention with the access door removed;

Fig. 2 is a vertical view in cross section taken substantially on the line 2—2 of Fig. 1, looking in the direction of the arrows, with the access door shown in elevation;

Fig. 3 is a sectional view taken substantially on the line 3—3 of Fig. 2, looking in the direction of the arrows;

Fig. 4 is a diagrammatic illustration of the refrigerating system of the refrigerator; and

Figs. 5, 6, 7 and 8 are isometric views of parts of the cabinet arranged to illustrate the order and manner of their assembly.

Before explaining in detail the present invention it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring now more particularly to the drawings, it will be observed that a domestic refrigerator is formed of an outer shell 10 having interconnected back, side, top and bottom walls 12, 14, 16 and 18, respectively. The bottom wall 18 includes an upwardly extending angular portion 19. The side, top and bottom walls 14, 16 and 18 are reversely contoured, as illustrated in Figs. 2 and 3, to provide spaced oppositely directed channels 20 acting as guides to receive outwardly extended flanges 22 and 48 of an inner liner 24, preferably formed of non-conducting material.

The liner 24 may be formed in any suitable manner, as by a plastic molding or forming operation, to provide interconnected back, side, top and bottom walls 26, 28, 30 and 32, respectively, spaced from and extending parallel with the walls 12, 14, 16, 18 and 19 of the outer shell 10 to provide an insulation space therebetween.

The walls of the liner 24 may be contoured with reference to the walls of the cabinet where differential temperature is involved to provide greater insulation space surrounding sections of the cabinet where lower temperature is desired. For example, if a portion of the space within the liner 24 forms an ice freezing compartment, the walls of the liner may be offset inwardly to provide greater insulation surrounding the ice freezing compartment.

As illustrated more clearly in Fig. 3, the side walls 14 of the outer shell or cabinet have inwardly directed flanges 36 extending substantially at right angles thereto contoured, as illustrated at 38, to provide the oppositely disposed vertically extending channels 20 to receive the flanges 22 of the liner 24. The contoured section defining the channels extends substantially parallel with the side walls 14 of the cabinet for a short distance, as illustrated at 40, to provide desired width of the channel 20 to receive the outwardly extended flanges 22 of the side members 28 of the inner shell 24. The contoured portion 40 preferably contacts the outer walls 14 to provide a more rigid and stronger structure. The sheet 14 is again contoured to provide a substantially right angle surface extending generally parallel with the flange 36, as illustrated at 42, to overlie a portion of the outwardly extending flange 22 of the liner 24 to extend beyond the inwardly directed flange 36 of the outer shell or cabinet.

Suitable fastening means, such, for example, as screws or rivets 44, may be projected through the outwardly extended flanges 22 of the inner shell 24 to project through the flange 42 of the outer shell or cabinet as illustrated to secure the inner and outer shells together.

The top panel 16 of the outer shell 10 is contoured in a similar manner, as illustrated at 46, to provide a channel to receive an upwardly directed flange 48 formed integrally with the top surface 30 of the inner shell 24. The lower wall 18 of the outer shell is also provided with a contoured portion, as illustrated at 50 to provide a similar channel 20' to receive a downwardly extended flange 52 carried by the lower surface 32 of the inner shell 24.

The back wall 26 of the inner shell 24 is preferably contoured, as illustrated at 54, to provide an angularly inclined section extending across the rear of the cabinet parallel with angular wall section 19. Heat insulation 55, preferably in batt form, is disposed between angular liner section 54 and angular casing wall 19. The section 19 and side walls 14 cooperate to provide a mechanism compartment 56 to receive and partially overlie a motor-compressor unit 58. A flue 59 is secured to the back wall 12 of the outer casing adjacent the mechanism compartment 56 to induce a flow of convection cooling air currents to dissipate heat from the motor-compressor unit 58.

With particular reference to Figs. 5, 6, 7, and 8, my improved method of making a refrigerator cabinet is as follows: The back, side and top walls 12, 14 and 16 of the outer shell 10, having the retainer structure 20, may be fabricated and secured together in any suitable manner, as by welding. To the other or rear edge of the casing section I secure, such as by welding operation, the upper rear panel portion 12 and into the casing proper thus formed I first place the heat insulation 34 against the sides, top and rear wall portion which insulation may be of the batt type

or any suitable type which will hold its shape. Utilizing the one piece liner 24, the outturned side flanges 36 thereof are engaged in the channels 20 at the bottom edges of the casing sides 5 14 and slid along the channels until the liner upper flange 48 is properly engaged in the top channel of the casing top wall. The liner 24 and the casing section are attached together by the screws 44 which extend through the liner side 10 and top flanges and screw thread into the casing flanges. Panel 19 is then utilized to close the bottom of the casing, but prior to application of the panel, the insulation 55 is positioned against the inclined rear wall of the liner or if desired, 15 the insulation may be attached to the panel and with the panel as a unit be attached to the casing. In either case, the retainer groove or channel 50 along the lower front edge of the panel 19 is engaged over the lower edge flange 52 of the liner 24 and is attached in place, completing the box-like casing and locking the liner in place. Then the panel 19 is attached to rear wall 12 such as by welding and to the bottom edge flange 20 of the liner by the screws 44. Thus, it will be seen that by my method the refrigerator cabinet 25 is readily assembled by simply inserting the one piece liner into the casing after first placing insulation in the latter and then applying the bottom insulation and casing panel to complete the structure.

An ice freezing compartment 70 may be positioned in the space within the inner shell 24 and be secured thereto in any suitable manner. A plurality of spaced shelves 72 may be provided to 35 divide the space within the food storage compartment within the inner shell 24 beneath the ice freezing compartment 70.

If desired, spaced drawers 74 having contoured back portions to align with the contoured portion 54 of the inner shell 24 may be provided for the reception of articles that cannot conveniently be positioned on the shelves 72.

An access door 76, having an outer metal wall 78 and preferably an inner wall 80 preferably formed of non-conducting material, is hinged to 45 one side of the outer side walls 14 to close the food storage compartment. Suitable insulation may be interposed between the door walls 79 and 80 to provide substantially equal insulation surrounding the entire food storage compartment.

50 A refrigerant condenser is preferably formed of interconnected tubes 82 bonded in heat exchange relation with the walls of the outer shell 10 to use the outer surface of the cabinet as a heat dissipating member. As illustrated, the tubes 82 are bonded to the back and top walls of the shell 10. It will be understood that if desired the refrigerant condenser and tubes may be bonded to all of the outer walls of the shell 10. The ice freezing compartment 70 is provided with a refrigerant evaporator 84, as illustrated diagrammatically in Fig. 4. The refrigeration cycle of this invention is as follows:

55 Gaseous refrigerant is withdrawn from spaced headers 86 of the evaporator 84, and is directed through a conduit 88 to the inlet side of the motor-compressor unit 58. The gaseous refrigerant is compressed by the motor-compressor unit 58 and is discharged to the refrigerant condenser 82 bonded in heat exchange relation to the outer shell of the cabinet. As heat is dissipated from the compressed gaseous refrigerant it is converted to the liquid form and passes 60 through a strainer 90 and a small diameter metering tube 91. The liquid refrigerant is then 65

directed to the refrigerant evaporator 84 where it is again expanded and converted into the gaseous form absorbing heat from the surrounding atmosphere to provide the desired refrigerated effect.

Although only a preferred form of the invention has been illustrated, and that form described in detail, it will be apparent to those skilled in the art that various modifications may be made therein without departing from the spirit of the invention or from the scope of the appending claims.

I claim:

1. The method of making a refrigerator cabinet which comprises, forming sheet material into a cabinet section of opposite side walls, a connecting wall with said side walls and inwardly directed retainer grooves along one edge of the section, attaching a panel to the opposite edge of the section to form therewith a box-like casing proper open opposite the connecting wall and opposite the panel, inserting insulation into the box-like casing proper, forming a one-piece box-like liner having outturned flanges along opposite and adjacent sides, engaging the opposite side flanges of the liner respectively in opposite side grooves of the casing proper through the opening opposite the connecting wall and sliding the liner into the casing inwardly of the insulation until the leading adjacent side flange engages in the retainer groove of the connecting wall, forming a casing panel with a retainer groove along one edge thereof, closing with insulation the opening opposite said connecting wall, and then attaching the panel to the casing proper with the panel groove receiving the other of the adjacent wall flanges to complete the casing and lock the liner thereto.

2. The method of making a refrigerator cabinet which comprises, forming sheet material into a cabinet section of opposite side walls, a connecting wall with said side walls and parallel extending inwardly directed flanges with a groove therebetween along one edge of the section, attaching a panel to the opposite edge of the section to form therewith a box-like casing proper open opposite the connecting wall and opposite the panel, inserting insulation into the box-like casing proper, forming a one-piece box-like liner having outturned flanges along opposite and adjacent sides, engaging the opposite side flanges of the liner respectively in opposite side grooves of the casing proper through the opening oppo-

site the connecting wall and sliding the liner into the casing inwardly of the insulation until the leading adjacent side flange engages in the retainer groove of the connecting wall, forming a casing panel with a retainer groove along one edge thereof, closing with insulation the opening opposite said connecting wall, and then attaching the panel to the casing proper with the panel groove receiving the other of the adjacent wall flanges to complete the casing and lock the liner thereto.

3. The method of making a refrigerator cabinet which comprises, forming sheet material into a cabinet section of opposite side walls and one connecting wall with the side and connecting walls formed along one edge thereof with inwardly extending substantially parallel flanges forming inwardly directed grooves therebetween, attaching a panel to the opposite edge of the section to form therewith a box-like casing proper open opposite the connecting wall and opposite the panel, inserting insulation into the box-like casing proper, utilizing a one-piece box-like liner having outturned flanges along opposite and adjacent sides, engaging the opposite side flanges of the liner respectively in opposite side grooves of the casing proper through the opening opposite the connecting wall and sliding the liner into the casing inwardly of the insulation until the leading adjacent side flange engages in the retainer groove of the connecting wall, utilizing a casing panel formed with a retainer groove along one edge thereof, closing with insulation the opening opposite said connecting wall, and then attaching the panel to the casing proper with the panel groove receiving the other of the adjacent wall flanges to complete the casing and lock the liner thereto.
